F. W. MILLER.

BOILER WASHING AND FILLING SYSTEM.

APPLICATION FILED MAY 7, 1917.

1,330,085.

Patented Feb. 10, 1920.

UNITED STATES PATENT OFFICE.

FRANK W. MILLER, OF CHICAGO, ILLINOIS.

BOILER WASHING AND FILLING SYSTEM.

1,330,085.

Specification of Letters Patent. Patented Feb. 10, 1920.

Application filed May 7, 1917. Serial No. 167,056.

To all whom it may concern:

Be it known that I, FRANK W. MILLER, a citizen of the United States, residing at Chicago, in the county of Cook and State of Illinois, have invented certain new and useful Improvements in Boiler Washing and Filling Systems, of which the following is a specification.

This invention relates to boiler washing and filling systems by means of which locomotives are blown off, washed out and subsequently refilled with hot fresh water preparatory to being put into service again.

One of the primary objects of my present invention is the provision of a system of this general character which will be highly efficient and economical in service and capable of being installed at a moderate price.

With this end in view I have devised an apparatus for separating the blow-off steam and water from the locomotive at or near the round-house pit where the locomotive is blown off, and for conveying the separated steam and water respectively to the tanks containing the refilling water and the washout water so that the steam is utilized for heating the refilling water and the blow-off water is stored for use as washout water.

With a view of maintaining a circulation of the water in the washout and refilling lines, so that the water will not cool down below the required temperatures but will always be present at the drops at suitable temperature for use, I have connected the end of the refilling line with the steam blow-off line so that the refilling water is returned through the steam blow-off line to the filling water tank, and have likewise connected the end of the washout line with the blow-off water line so that the washout water is circulated through the blow-off water line back to the washout tank, thus I have provided for an adequate circulation of water in both the washout and refilling lines without the installation of additional circulating pipe lines.

Another purpose of my invention is to provide for the delivery of washout water to the drops at the requisite temperature for washing out a boiler. Since the water in the washout tank is customarily at a higher temperature than that at which the washer can handle the washout nozzle it has

heretofore been proposed to temper this water by admitting cold water to the intake pipe of the washout pump. In large round-houses where the washout line is of considerable length the washout water, if delivered at the proper temperature by the pump, will be considerably reduced in temperature and, consequently, too cold before it reaches the washout drop. I have accordingly provided in my present invention for tempering the washout water at a point remote from the pump by automatically admitting cold water thereto in sufficient quantities to produce the required temperature of the washout water. In this connection I have also provided novel apparatus for mixing the cold water with the washout water without the utilization of a mixing and pressure equalizing tank, which has heretofore been considered indispensable when the water in the washout line and in the cold water line were at different pressures.

Another object of my invention is to condense at least a portion of the steam in the blow-off steam line before it enters the refilling tank so as to produce a partial vacuum in this line which will facilitate the blowing off operation.

Other objects and many of the attendant advantages of this invention will be readily appreciated by those skilled in the art as the same becomes better understood by reference to the following description when considered in connection with the accompanying drawings, on which the single figure represents somewhat diagrammatically an elevational view of a boiler-washing and filling system embodying my invention.

Referring to the drawings it will be observed that the system comprises essentially a washout tank 5, adapted to contain a quantity of water to be used for washout purposes, and a filling water tank 6, adapted to contain a quantity of water to be used for refilling a blown off locomotive. While these tanks are shown as structurally independent they may, of course, be formed as a single unit divided into washout and refilling compartments by a partition, and obviously the tanks may be made of wood, steel or other suitable material.

In the roundhouse the post of each pit at which washout and refilling operations are designed to take place, is equipped with

a refilling drop 7, a washout drop 8, and a blow-off drop 9, the blow-off and refilling drops being adapted to be connected with the boiler through the intermediary of flexible hose in the usual manner, and the washout drop being equipped with a hose provided with a washout nozzle, all of which are well known in the art. The blow-off drop is connected by suitable piping with the blow-off steam main 11, the piping between the drop and the main being constructed to include a T connection 12, the lower leg of which is connected with the blow-off water main 13. The purpose of this T connection 12 is to separate the blow-off steam from the blow-off water so that the blow-off steam will be conducted through the blow-off steam main 11 to the filling water tank while the blow-off water will be conducted through the blow off water main 13 to the washout tank. Any other suitable construction might be employed for separating the blow-off steam and water but I have found that the structure disclosed is cheap, simple and satisfactory. The blow-off steam is conducted through the main 11 to a vertical pipe 14 which extends downwardly into the refilling tank 6 below the water level therein and is equipped at its lower end with a muffler or steam distributor through which the steam is noiselessly delivered into the surrounding water to heat the same. The blow-off main 11 is also preferably equipped with steam blow-off drops 10 which may be connected to the dome of a locomotive so that steam may be blown off through this drop at the same time that steam and water is blown off through the drop 9, thereby enabling the locomotive to be blown down more quickly than it could be through the drop 9 alone. The blow-off water is conducted by the main 13 to a scale pocket or sludge receptacle 16 where the scale, sludge and other heavy impurities are collected and from which they may be delivered at intervals through a pipe 17 to the sewer. The blow-off water which has been relieved of these heavy impurities in the scale pocket is then conducted through a pipe 18 to the washout tank where it is delivered through perforated distributing pipes 19 beneath the surface of the water in the tank.

The water level in the washout tank is maintained by admitting cold water from a pipe 21 connected with the city main or any suitable source of fresh water supply, this supply pipe being provided with a branch pipe 22 which delivers into the washout tank. The admission of water to the washout tank through this pipe is regulated by a float valve 23 located in the pipe 22 and automatically controlled by the water level in the washout tank through the medium of a suitable float mechanism 24 connected with

the tank. The pipe 22 is also preferably equipped with a hand valve 25 by means of which the water supply to the washout tank may be entirely shut off should occasion require.

Water from the washout tank 5 is delivered to the washout drops 8 through a washout main 26 by means of a pump 27 having its intake 28 connected with the tank 5 near the bottom thereof. This pump is preferably steam driven and the steam for this purpose is received through a branch pipe 28' from a live steam supply pipe 29 connected with a steam boiler in the power house. The speed of the pump is regulated by the back pressure of the water in the washout line through the instrumentality of pressure controlled mechanism designated generally by reference character 31, which mechanism may be of any well known or preferred construction.

Since the water in the washout tank is usually hotter than it can be handled by the operator who manipulates the washout nozzle, it is desirable to temper this water by the admission of cold water in limited quantities. In order that the water may be delivered to the washout drops at the requisite temperature I have provided for admitting cold water to the washout line in requisite quantities at a point remote from the pump, so that the temperature of the washout water will not drop materially before it reaches the point of use. With this end in view the washout main is equipped with a Y-connection 32, comprising a nozzle 33 through which the washout water from the tank 5 is delivered. A pipe 34 connected with the main cold water supply pipe 21 is connected with one branch of the Y-connection 32, so that the water delivered through the nozzle 33 will draw in cold water by an injector action, thus thoroughly mixing the hot and cold water and insuring the admixture of the waters irrespective of the differences in pressure between the water in the pipe 32 and the water delivered by the pump 27. In order that the requisite amount of cold water may be admitted to the washout main the pipe 34 is equipped with a thermostatically controlled valve 35 which is actuated and controlled by a thermostatic element, of well known construction, projecting into the washout main beyond the point of admission of the cold water, this element being connected with the valve 35 by a connecting tube 36, so that expansion and contraction of the element will serve to open and close the valve. In case it should be desirable to entirely shut off the cold water this may be done by means of a hand valve 37 interposed in the pipe 34 in any convenient location. It will thus be seen that I am able to automatically temper the wash-

out water without the use of a mixing tank and at a point remote from the washout pump, so that the washout water will be delivered at the drop at suitable temperature 5 for washing out a boiler. For emergency purposes a connection is made between the cold water supply pipe 21 and the intake pipe 28 of the washout pump by means of a pipe 38 equipped with a hand valve 39 10 which is normally closed.

The water level in the refilling tank 6 is maintained by the admission of clean fresh water thereto from the cold water supply 15 21 through a branch pipe 41, which it will be observed is connected with the blow-off steam pipe 14 through a T connection 42, so that cold water is admitted to this pipe to partially condense the blow-off steam before it reaches the tank 6, thereby producing 20 a partial vacuum in the blow-off steam main which facilitates the blowing off operation. The admission of water through the pipe 41 is regulated by a float valve 43, which is controlled by a float 44 connected with the 25 interior of the tank 6 and actuated by variations in the water level in the tank. The supply of water to the tank may be entirely shut off when required by a hand valve 40 interposed in the branch pipe 41. In order 30 to maintain the refilling water at the requisite temperature I propose to admit live steam from the supply pipe 29 through a branch pipe 45, the admission of steam to the tank 6 being regulated by a valve 46 35 which is actuated and controlled by a thermostat 47 projecting into the tank.

The refilling water from the tank 6 is delivered to the refilling drop 7 through a refilling main 48 by means of a pump 49 40 similar to the washout pump 27 driven by steam admitted from the supply pipe 29 through a branch 51 and controlled by a pressure controlled regulator 52 in a well known manner.

45 The blow-off steam which is principally relied upon to heat the refilling water in the tank 6 is supplemented by the exhaust steam from the pumps 27 and 49, which exhaust steam is delivered from the pumps 50 through the branches 53 and 54 respectively, to a pipe 55 which is connected with the steam delivery pipe 14, and if preferred the exhaust steam from the power house may also be delivered into the pipe 14 through 55 a pipe 56. The pipe 55 is preferably equipped with a check valve 57 which will prevent the pressure from backing up in the pipe 55 in the event of accumulation of excess pressure in the pipe 14.

60 In order to maintain a circulation of the refilling water in the refilling main 48 so that the water will not cool down in the long length of pipe incorporated in the refilling main I have connected the end of the refilling main with the end of the steam blow-off

main, as indicated by reference 58. The refilling water therefore travels to the end of the refilling line under pressure of the pump 49 and is then returned to the refilling tank through the steam blow-off main 11. Similarly, to maintain a circulation of the washout water in the washout main sufficient to insure at all times water of the requisite temperature at the drops I have connected the end of the washout main with the blow-off water main by means of a pipe 59. The washout water therefore travels to the end of the main under pressure from the pump 27 and is returned through the blow-off water main 13 and the pipe 18 to the washout tank. It will be evident therefore that I am able to effect the desired circulation of both the refilling and the washout water without the necessity of installing additional or separate circulating mains, such as have heretofore been employed for circulating the refilling and washout waters and returning them to their respective tanks. 75 80 85

It is believed that from the foregoing it will be understood that I have provided 90 a boiler washing and filling system which is simple in construction and highly efficient in operation, but I do not wish to be restricted to the specific embodiment of the invention illustrated and described, as it 95 is capable of considerable modification and variation within the scope of the invention as defined in the following claims.

I claim:

1. A boiler washing and filling system, 100 comprising washout and refilling tanks, washout and refilling lines connected with their respective tanks, blow-off lines for conducting blow-off steam and water respectively to the refilling and washout tanks, 105 and connections between various of said lines whereby the refilling and washout waters are returned through said blow-off lines to their respective tanks.

2. A boiler washing and filling system, 110 comprising washout and refilling tanks, washout and refilling lines, a blow-off steam line connected with the end of said refilling line through which refilling water is returned to the refilling tank, a blow-off water 115 line connected with the end of said washout line and through which washout water is returned to said washout tank, and means for separating the blown-off steam and water and delivering the same to said blow off 120 steam line and said blow off water line respectively.

3. A boiler washing and filling system, 125 comprising washout and refilling tanks, washout and refilling mains for delivering water from said tanks respectively, a blow-off drop, means adjacent to the drop for separating blown off steam and water, a blow-off steam main and a blow-off water main for conducting said steam and water 130

to said refilling tank and washout tank respectively, a connection between the refilling main and said blow-off steam main, and a connection between said washout main and said blow-off water main through which said blow-off steam and water mains serve as return circulating lines for said refilling and washout mains respectively.

4. A boiler washing and filling system, comprising washout and refilling tanks, washout and refilling mains, a blow-off drop, means adjacent the drop for separating the blown off steam and water, a blow-off steam main for conducting said blown off steam to said refilling tank, a blow-off water main for conducting said blown off water to said washout tank, and means interposed in said

blow-off water main for removing the scale, sludge and the like from said blow-off water.

5. A boiler washing and filling system, comprising washout and refilling tanks, washout and refilling lines, a blow-off steam line, a blow-off water line, means for separating the blow-off steam and water and delivering the same to said blow-off steam line and blow-off water line, respectively, and a connection between said washout line and said blow-off water line through which washout water is returned through said blow-off water line to said washout tank to maintain a circulation of water in said washout line.

FRANK W. MILLER.
